Primary Examiner — Jeffrey D Asch(74) *Attorney, Agent, or Firm* — NSIP Law(57) **CLAIM**

I claim the ornamental design for an electronic device, as shown and described.

DESCRIPTION

FIG. 1 is a front perspective view of an electronic device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The evenly broken lines that show features of the article throughout the views, which are immediately adjacent to the shaded areas and define unshaded regions, represent the bounds of the claimed design. The dot dash broken lines, which are immediately adjacent to the shaded areas and define unshaded regions, represent the bounds of the claimed design. All other broken lines are directed to environment. The broken lines form no part of the claimed design.
